(57) **CLAIM**

The ornamental design for our handle, as shown and described.

DESCRIPTION

FIG. 1 is a perspective view of our handle in accordance with our new design;

FIG. 2 is another perspective view of our handle;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in FIG. 2 are for illustrative purposes only and form no part of the claimed design.

1 Claim, 5 Drawing Sheets

FIG. 1

FIG. 2

FIG. 3

FIG. 4

FIG. 5

FIG. 6

FIG. 7

FIG. 8
